UNITED STATES PATENT OFFICE.

JOHN C. BRYAN, OF HOLLY SPRINGS, ARKANSAS.

CAR-COUPING.

SPECIFICATION forming part of Letters Patent No. 291,572, dated January 8, 1884.

Application filed May 4, 1883. (No model.)

To all whom it may concern:

Be it known that I, JOHN C. BRYAN, a citizen of the United States, residing at Holly Springs, in the county of Dallas and State of 5 Arkansas, have invented a new and useful Improvement in Car-Couplings, of which the following is a specification.

This invention relates to car-coupling devices, and has for its object to provide a car-coupling which will be automatic in its operation, and one that may be operated from the top or either side of the car, thus avoiding the great danger attendant upon entering between the cars for the purpose of coupling them.

15 The invention consists in the novel mechanism employed for the accomplishment of these objects, as hereinafter described and claimed.

To enable those skilled in the art to make and use my invention, reference should be had 20 to the accompanying drawings, in which—

Figure 1 is a plan view of a platform-car inverted, having my improvements applied. Fig. 2 is a vertical longitudinal section of the same. Fig. 3 is a side view of the draw-head 25 attachment, and Fig. 4 is an end view of the draw-head. Fig. 5 is a detail view.

The U-shaped frame A is loosely attached to the draw-head B by clips, as shown at a a', with its points downward. This frame A is 30 intended to carry the coupling-pin a', which is attached to its center, while to its lower ends is attached the apron C, which is intended to guide the link on its entrance into the draw-head. The apron is provided with 35 a spring or arm, c, which is adapted to bear against the under side of the draw-head, when the frame A is raised, in such manner as to hold it raised (see full lines, Fig. 1, and dotted lines, Fig. 2) at an angle of about thirty degrees below the horizon, in which position it 40 will receive and guide the link into the mouth of the draw-head, whether the cars be of the same or different heights. The apron is pivoted to the frame A, and the latter has vertical rods or bars that work in clips or guides a a', attached to the sides of the draw-head.

45 D D indicate elbow-levers, which are pivoted to fixed portions of the frame-work C' of the car.

50 E is a bifurcated rod, the forked projections of which are attached to the upper ends of the

elbow-levers D, while the other extremity passes through a girder of the car and is attached to the chain or hook K, which is attached to the lever system composed of the 55 levers F, G, and H and links f.

g is a spiral retaining-spring connected to the lever E, for the purpose of forcing it forward when not held back by the levers.

J is a sliding rod supported underneath the 60 girder, and adapted to shift a pivoted catch, N, to cause it to engage with a shoulder on the rod E to lock it, for the purpose of holding up the pin a', so as to prevent the cars from coupling, when so desired.

65

This coupling device can be operated from the left of the car by means of the lever F, from the right of the car by the lever G, and from the top of the car by the lever H.

The construction, attachment, and mode of 70 operation of these several levers is obvious and need no explanation, except, perhaps, to say that either may be provided with proper catches to hold them when forced back, so that it will be impossible to couple the car until 75 the lever is released, thus performing the work which the rod J is designed to perform.

From the above description of my device, together with the accompanying drawings, its mode of operation will be readily understood 80 to be as follows: Any one of the levers F, G, and H being forced backward by the operator will cause the rod E to throw elbow-levers D into the position shown in full lines, Fig. 1, and dotted lines, Fig. 2—that is to say, 85 the upper arms of said levers D being drawn backward, their lower ends are forced forward and upward, carrying with them the frame A and apron C, which movement is continued until the coupling-pin a' has risen 90 far enough to clear the upper edge of the trip or throat-plate i, when the latter will be forced forward by the spiral spring k in rear of it and pass beneath the pin a', so as to hold it raised in the position (Fig. 2) required for coupling 95 automatically—that is to say, when the link of an approaching car strikes upon the inclined apron C, it will be guided upward into the draw-head B and strike the trip-plate i, force it backward, and thus the support of the pin 100 a' being removed, it will fall by gravity, and, passing through the link, couple the cars.

It is obvious that the elbow-levers D, apron-guide C, and U-shaped frame A also drop with the pin a' into the original and normal position.

5 The trip-plate i is preferably secured to the end of a rod encircled by the spring k , and its upper and lower edges are respectively turned forward and backward to afford support for the coupling-pin, and to furnish a broad base 10 to rest on the floor of the draw-head.

What I claim is—

1. In a car-coupling, the combination of the U-shaped frame carrying the coupling-pin, the trip-plate i , and spring k for acting thereon, the apron-guide, and levers for raising said pin, frame, and guide, substantially as specified.

2. In a car-coupling, the combination of the apron C, having spring c , and the oscillating

elbow-levers D, whereby the frame A and 20 apron C may be raised by means of a system of levers, all as shown and described.

3. In a car-coupling, the combination, with the frame A and oscillating levers D, of the bifurcated spring-retained lever E and the 25 rod J, adapted to hold said lever against the action of its spring, substantially as set forth.

4. The combination, with a draw-head, of a sliding frame carrying the coupling-pin, a link-guiding apron attached to the lower part of 30 said frame, and a suitable device for lifting said frame to withdraw the pin and guide the link into the draw-head, substantially as shown and described.

JOHN C. BRYAN.
